DIAPER PIN

Herbert F. Heyden, Jackson Heights, N.Y., assignor to Baby World Company, Inc., Long Island City, N.Y., a corporation of New York

Application February 13, 1958, Serial No. 715,012

3 Claims. (Cl. 24—156)

This invention relates generally to fastening devices, 15 and especially concerned with fastening devices of the safety pin type.

As is well known, especially in the care of babies, conventional safety pins are not entirely safe, being the direct cause of not infrequent accidents resulting from inadvertent opening of a safety pin by the manipulation or body movement of a child. That is, conventional safety pins have been found to accidentally open, and thereby expose the sharp free end point, without any directed effort toward this end.

It is therefore one object of the present invention to provide a novel safety pin construction which, although relatively easy to open and close for an adult capable of coordinated effort to positively direct the free leg, is effectively prevented from being unintentionally opened by the manipulations and body actions of a child.

It is another object of the present invention to provide a unique safety pin construction which is extremely simple, sturdy and durable in use, and capable of being manufactured and sold at a reasonable cost.

Other objects of the present invention will become apparent upon reading the following specification and referring to the accompanying drawings, which form a material part of this disclosure.

The invention accordingly consists in the features of construction, combinations of elements, and arrangements of parts, which will be exemplified in the construction hereinafter described, and of which the scope will be indicated by the appended claims.

In the drawings:

Figure 1 is a longitudinal view showing a safety pin of the present invention in closed condition;

Figure 2 is a longitudinal view showing the safety pin of Figure 1 and taken at right angles with respect to the latter;

Figure 3 is a longitudinal view similar to Figure 1, but showing the safety pin in its open condition;

Figure 4 is a transverse sectional view taken substantially along the line 4—4 of Figure 1, showing the safety pin in its closed condition; and

Figure 5 is a partial, longitudinal sectional view taken substantially along the line 5—5 of Figure 1.

Referring now more particularly to the drawings, the safety pin of the present invention, as illustrated therein, includes a pair of front and back legs 10 and 11 resiliently connected together at one pair of adjacent ends, and a protective cap, generally designated 12 adjacent to the other leg ends. In any conventional manner, the legs 10 and 11 may be resiliently connected together at one pair of adjacent ends, as by a convolution or coil 13 integral with the legs. Thus, the front and back legs 10 and 11 are normally disposed, in their unstressed condition, in diverging relation away from the connected ends or joint 13, and resiliently movable toward each other. The protective head or cap 12 is carried fixedly on one end of the leg 11 remote from the connection 13, while the end of front leg 10 remote from the connection

2

is free, as at 14, for swinging movement toward and away from the back leg 11.

The protective head 12 is advantageously fabricated of plastic, or other suitable material, and generally of a flattened cup-shape lying approximately in the plane of legs 10 and 11. As best seen in Figure 4, the cup-shaped member or head 12 is of generally ovaloid configuration, both interiorly and exteriorly, in its transverse cross section.

10 It may be considered that the ovaloid shaped cup-member or head 12 includes front and back end walls 18 and 19, respectively, and side walls 20 and 21 extending between the end walls. The head 12 is fixedly secured to the back leg 11 by having the region of said leg remote from said leg connection 13, as at 22, embedded in the head end wall 19. In this fixedly secured relation on the back leg 11, the head 12 extends generally from the back leg towards the front leg 10, and is arranged with its internal cavity or hollow facing toward the leg connection 13. Stated otherwise, the head 12 is closed at its outermost region 23, longitudinally of the safety pin, and opens longitudinally inward of the safety pin toward the opposite safety pin end at the leg connection 13.

In one side wall of the cup-shaped member or head 12 the side wall 20, at a location adjacent to but spaced from the end wall 19, there is provided a through opening or slot 25 extending from the inner edge of wall 20 toward and terminating short of the distal head region 23, and opening laterally between interior and exterior of the head. More specifically, the opening or slot 25 is located in spaced relation intermediate the end wall 19 and the minor axis of the ovaloid member. The opening 25 is adapted to pass therethrough the free end 14 of front leg when the latter is resiliently directed laterally through the opening. In Figure 4 it is best seen that the free end of front leg 14 is received within the cup-shaped element or head 12 and by its tendency to move toward its open position of Figure 3, is resiliently retained in bearing engagement against the head end wall 18.

In addition, the head 12 is provided with an internal wall 28 extending from the end wall 19 generally along the major axis of the ovaloid head so as to be centrally spaced in relation with respect to the side walls 20 and 21. The wall 28 extends past the side wall opening 25 and the minor ovaloid axis toward and terminates short of the opposite or front end wall 18. Also, the internal wall 28 may join or be integral with the longitudinally outer head wall 23 and have its inner edge substantially flush with the inner edges of the side walls 20 and 21, as best seen in Figure 5. The terminal region of the internal wall 28 is advantageously enlarged, as at 29, beyond the minor axis of the ovaloid head, which enlargement is preferably symmetrical about the major axis of the ovaloid. The terminal enlargement 29 is formed with 50 a recess or groove 30 which faces toward the end wall 18 and subdivides the enlargement into furcations 31 and 32 extending respectively toward and spaced from the side walls 20 and 21 at locations intermediate the end wall 18 and minor axis of the ovaloid shaped head.

60 It will now be appreciated that the internal wall 28 and its enlargement 29 combine with the remainder of the head 12 to define a pair of passageways 33, 34 on opposite sides of the internal wall respectively adjacent to the side walls 20 and 21. Further, each of the passageways 33 and 34 extend from the end wall 19 to the end wall 18, and the passageways communicate with each other in the region adjacent to the latter end wall. Also, the enlargement 29, and more specifically its furcations 31 and 32 serve to restrict the passages 33 and 34, respectively, to a minimum dimension slightly greater than the thickness of the received free leg end 14. Thus, mere squeezing together of the legs 10 and 11, or other

undirected movement of the leg 10 toward leg 11, from the closed condition of Figure 4, will move the free end of the former leg through one of the passages 34 or 33 to engagement with the end wall 19, or into the recess 30, none of which will enable the safety pin to open. It is only upon positive direction of the free leg end 14 first through the constriction of passageway 43 between wall 20 and furcation 31, and then laterally outward through opening 25, that the leg 10 may be released from its captive relation within the head 12.

From the foregoing, it is seen that the present invention provides a safety pin which fully accomplishes its intended objects, and is well adapted to meet practical conditions of manufacture and use.

Although the present invention has been described in some detail by way of illustration and example for purposes of clarity of understanding, it is understood that certain changes and modifications may be made within the spirit of the invention and scope of the appended claims.

What is claimed is:

1. A safety pin comprising a pair of front and back legs resiliently connected together at one pair of adjacent ends and normally diverging from said one ends in their unstressed condition, the other end of said front leg being free, and a protective head on the other end of said back leg for releasably retaining the free end of said front leg, said head comprising a flattened cup-shaped member having longitudinally extending side walls and end walls and arranged with one end wall fixed to said back leg and extending therefrom generally toward said front leg with its internal cavity opening toward said connected leg ends, said cup-shaped member being formed in a side wall thereof with a laterally extending through opening adjacent to and spaced from said one end wall 35 for passing therethrough the free end of said front leg, said free end of said front leg being normally in resilient bearing engagement with the other end wall of said cup-shaped member when received in the latter, and an internal wall in said cup-shaped member extending from 40

said one end wall in centrally spaced relation with respect to said side walls beyond said side wall opening toward and terminating short of said other end wall, said internal wall combining with said cup-shaped member to define a pair of passageways on opposite sides of said internal wall extending from said one end wall to and communicating with each other in the region of said other end wall, whereby said free front leg end is movable from said normal position in said cup-shaped member 5 through either of said passageways into engagement with said one end wall beyond said through opening, said internal wall obstructing removal of said free front leg end when in the passageway remote from said through opening and said free front leg end being removable through said through opening only by positive lateral direction when in the passageway adjacent to said opening.

2. A safety pin according to claim 1, in combination with an enlargement on the terminal region of said internal wall to restrict said passageways to dimensions only slightly larger than that of said free front leg end.

3. A safety pin according to claim 2, wherein the enlargement is formed with a recess facing toward said other end wall for receiving said free front leg end and further obstructing its undirected removal from said cup-shaped member.
